UNITED STATES PATENT OFFICE.

WILLIAM M. HOUGHTON, OF NEWTON, MASSACHUSETTS.

DIPPER-LATCH ACTUATOR.

Application filed July 2, 1927. Serial No. 203,104.

This invention pertains to power shovels or the like of that kind in which the dipper of the apparatus is provided with a movable closure or door which is normally held closed by a latch, the present invention relating more particularly to means for releasing the latch so as to permit the door to open and release the contents of the dipper.

As usually constructed the latch is a sliding bar carried by the movable door of the dipper and normally engaging a keeper on the dipper body. When so constructed the latch sustains a substantial part of the weight of the contents of the filled dipper and considerable force (of the order of 1000 lbs. per cubic yard of dipper size) is required to withdraw the latch from the keeper. Owing to the difficulty of this operation it is frequently necessary for the shovel operator to use both hands in pulling the rope or other device for retracting the latch, thus obliging him to release his grip on the shovel operating levers. In some instances the operation of the latch pull rope is delegated to a helper but either mode of operation is wasteful of time and unsatisfactory. To avoid this difficulty certain attempts have been made to provide power means for releasing the latch (for example, small electric motors or power actuated clutch drives); but these arrangements have been expensive, relatively slow in action, and not wholly dependable.

In accordance with the present invention I have devised a latch actuator which withdraws the latch instantaneously by the release of stored up energy (such for example as that supplied by a stressed spring). Release of this energy may be accomplished with but slight effort on the part of the shovel operator and a new supply of energy is automatically stored up by the opening of the door or bottom member of the dipper, while the operative parts are so disposed or protected that they are not readily injured.

In the accompanying drawings I have illustrated certain embodiments by way of example and in the drawings

Fig. 1 is a diagrammatic side elevation of a complete power shovel of usual type, but embodying the present invention;

Fig. 2 is a fragmentary side elevation, to large scale, showing the rear part of the dipper body and a portion of the handle, together with one form of my improved latch actuating means, the door or closure member of the dipper being in normal closed position;

Fig. 3 is a view similar to Fig. 2 but showing the door of the dipper in its open position;

Fig. 4 is a fragmentary plan view, partly in section, showing certain details of a releasing catch for the latch actuating mechanism;

Fig. 5 is a fragmentary side elevation, similar to Fig. 2, but showing a modified construction;

Fig. 6 is a rear view of a dipper comprising the parts shown in Fig. 5;

Fig. 7 is a fragmentary rear view, partly in section, showing a modification of the section shown in Fig. 6; and

Fig. 8 is a vertical section, to smaller scale, on the line 8—8 of Fig. 2.

Referring to the drawings the numeral 1 designates a shovel apparatus or excavator of substantially usual construction comprising a revolving platform rotatably mounted upon a suitable base, such for example as the caterpillar tractor 2. The apparatus comprises the boom 4 carrying the dipper handle 5 which supports the dipper 6 at its outer end. 80 This dipper may be of any usual shape and is furnished with a movable closure or door 7. This door preferably comprises a pair of spaced hinge members 8 and 9 respectively (see Fig. 6) which are curved rearwardly 85 and upwardly and pivotally connected at 10 to the body of the dipper. The rear side of the door or closure 7 is furnished with suitable guides for a sliding latch bar 11 having a beveled forward end 12 adapted to engage 90 a keeper 13 carried by the dipper body, all in usual manner.

In accordance with the construction shown in Figs. 2, 3 and 4 I mount a rock shaft 14 in suitable bearings carried by the forward 95 end of the dipper handle 5 and on this shaft I mount a lever device here shown as having a short lever arm 15 and a long lever arm 16. I secure a spring housing 17 to the handle, such housing enclosing one or more springs 100 18, here shown as of coiled compression type, which rest upon the lower end of the housing and whose upper ends bear against a collar 19 fixed to a rod 20 whose lower end is pivotally attached at 21 to the short lever arm 15. 105

I also mount upon the forward end of the dipper handle a releasable catch member, here shown as a bell-crank lever pivoted at 22 and having the arm 23 provided at its forward end with a roller 24 constituting the catch 110 proper and which is adapted normally to engage the upper part of the long lever arm 16,

thus keeping the latter in the full line position shown in Fig. 2 with the springs 18 under compression. Preferably the free end of the long lever arm 16 is beveled as indicated at 5 to facilitate its reengagement with the catch roller 24. In order to protect the arm 16 and to keep it in proper relation to other parts, I preferably confine it between parallel guides 26.

10 The bell-crank catch lever also comprises an arm 27 to which one end of a suitable actuating element 28 is attached. This actuating element may be a light cord leading down into the operator's cab, or it may, if desired, be connected to a solenoid or equivalent device for moving the catch electrically. In order to maintain the catch lever in operative position, except when released by actuation of member 28, I provide a tension spring 15 29 secured at one end to the arm 27 and at its other end to a convenient fixed part.

About the shaft 14 I wrap a flexible connection 31, for example a chain whose other end is connected to the latch 11. This chain 25 permits the latch to reengage its keeper while the lever device occupies the position shown in Fig. 2. Although I may wind the chain 31 about shaft 14 as described, I may, if desired, connect the end of the chain to an arm 30 carried by the shaft 14, for example the arm 15, and the shaft may be considered as the equivalent of a lever in its operation in releasing the latch.

The long arm 16 of the lever device is connected to the dipper door, preferably by means of a pair of telescoping links. One link 33 is pivotally secured to the dipper door at the point 32, such link having an abutment shoulder 34. This link telescopes within the 40 tubular link 35 which is connected to the long lever arm 16 at 36, the free end 37 of the link 35 constitutes a second abutment engageable with the abutment 34 as herein-after described for moving the lever arm 16 45 in opposition to the spring 18.

In normal position, that is to say, when the dipper door is closed, the latch actuating mechanism occupies the position shown in Fig. 2, it being assumed that the dipper has been actuated to dig up a load of material and that such material is resting upon the door of the dipper. The door may be 50 opened to discharge this load by a slight pull upon the cord 28. The catch roller 55 24 may be moved quite easily so as to disengage it from the lever arm 16 and thereupon the spring 18 is free to expand, thus driving the collar 19 and rod 20 upwardly and rocking the shaft 14 in a clockwise direction. This winds up chain 31 and almost 60 instantly pulls the latch 11 out of engagement with its keeper, thus permitting the door to open under the weight of the contents of the dipper.

65 In the normal position of the parts, as shown

in Fig. 2, the end 37 of the tubular link 35 is spaced from the abutment 34 of the link 33 so that when the lever is released from its catch, it is free to swing down to the dotted line 16^a of Fig. 2. At the end of this movement the end 37 of the link 35 is substantially in contact with the abutment 34, and as the door begins to swing open under the weight of the load, the abutment 34 pushes the link 35 to the left, as viewed in Fig. 3, 70 thus compressing the spring 18 with a constantly increasing leverage due to the approach of the pivot 32 to the line defined by the pivots 10 and 36. As the door advances toward its fully opened position, the lever 80 16 assumes first the position 16^b of Fig. 3, where the beveled end 25 engages the roll 24, causing the latter to ride up over the beveled surface 25 until the long lever arm 16 escapes from beneath the roll as shown in Fig. 3. The 85 door may continue to open beyond this point, but due to the continued approach of the pivot 32 toward the line defined by the pivots 10 and 36 the corresponding movement of lever 16 grows less and less and although the 90 long lever arm may reach some such position as 16^d, the over travel is short. By properly proportioning the parts, the latch may be reset at almost any desired door opening. When the door again closes the long 95 lever arm 16 returns to the position 16^c where it is stopped by the catch roll 24. The spring 18 is compressed during the above operation so that the parts are restored to the position shown in Fig. 2. The door is free to close 100 and its closing may be accomplished in any usual manner, as for example by gravity, and when the door closes the abutment member 34 recedes from the link 35 and at the same time the latch 11 snaps into engagement with 105 its keeper 13, the chain 31 slackening and permitting this movement of the latch.

Thus as above described the large amount of stored up energy furnished by the spring 18 and which is sufficient to withdraw the 110 latch, is readily released by a slight pull on cord 28, while the action of the door in opening restores the spring to its normal stressed condition ready for the next subsequent operation. If for any reason the initial opening 115 of the door should not be enough to reset the spring, a slight shaking of the dipper, as is common for detaching sticky material, will swing the door sufficiently to reset the spring. It may be noted in this connection that the 120 spring may act to some extent at least as a shock absorber to prevent too rapid opening of the door.

Referring to Figs. 5 and 6 I have shown a modified arrangement in which the dipper door is provided with a pivot 40 forming a fulcrum for a lever comprising the long arm 41 and the relatively short arm 42. The long arm 41 is provided at its end with a recess 43 for engagement with a catch roll 44 mounted 130

upon a bell-crank catch lever having an actuating arm 45 to which one end of a cord 46 or other suitable actuating element is attached.

5 The free end 42^a of the lever arm 42 is disposed within an elongate slot in one end of a link 47. The other end of this link 47 (Fig. 5) is pivotally connected at 47^a to one end 48 of a lever pivotally mounted at 49 upon the 10 convenient part of the dipper door, for example the hinge 9. This lever also comprises an arm 50 which is pivotally connected to the link 51 whose other end is pivotally connected to the dipper body at 52. A heavy 15 leaf spring 53 is mounted upon the dipper door and one end of this spring is connected by means of a link 54 to the short lever arm 42.

In this arrangement the end of the lever arm 41 normally engages the catch roller 44, the spring 53 being under stress and the end 42^a of the arm 42 being disposed adjacent to the left-hand end of the slot in the link 47 as viewed in Fig. 5. The arm 41 of the lever 25 passes through an elongate opening 11^a in the latch 11 and when the catch roll 44 is released from the recess 43 of the lever arm 41, the spring 53, acting through link 54, suddenly swings lever arm 41 in a clockwise direction, 30 as viewed in Fig. 6, thus withdrawing the latch 11 from its keeper and moving the end 42^a of the lever arm 41 to the right-hand end of the slot 47. When the dipper door swings to open position, the fulcrum 49 is moved relatively to the pivot point 52, thus changing 35 the arrangement of the link and lever connections and exerting a powerful pull upon the end 42^a of the lever arm 42, thus again placing the spring 53 under stress. The 40 leverage increases as the spring is compressed and when the arm 43 passes the roller 44, it is reengaged by the latter, thus retaining the parts in normal position. By reason of the elongate slot 11^a in the latch, the latch is 45 now free to ride over its keeper thus again locking the door of the dipper in closed position.

In Fig. 7 I have illustrated a slight modification of the last-described arrangement, in 50 which I substitute a coiled spring for the leaf spring 53. This coiled spring 55 is mounted in a suitable housing 56 on the door of the dipper, and one end of this spring engages a collar 57 on a rod 58 pivotally secured at 59 to the arm 42 of the lever. This spring 55 operates in the same way as the spring 53 and need not be further described.

In the arrangement shown in Figs. 2 and 3 the latch actuating parts are mounted upon the shovel handle, while in the construction shown in Figs. 5, 6 and 7, the latch controlling parts are at the upper end of the door. Thus in the several forms of the apparatus, the moving parts are practically safe from injury in the normal operation of the shovel.

Moreover, the parts are simple, rugged, and durable and of a character such that they are not readily disturbed or injured, although, as above described, the release of the latch is quickly and easily accomplished by a slight 70 pull on a light cord, so that the shovel operator may dump the dipper by the use of one hand.

While I have shown and described certain desirable arrangements providing the desired 75 energy for releasing the latch instantly and for restoring this energy by the action of the weight of the dipper door or its contents, I wish it to be understood that the arrangements here shown are merely by way of example and are not to be considered as restricting or defining the invention but that other and equivalent means and arrangements of parts may be employed within the scope of the appended claims. 80

I claim:

1. Apparatus of the class described comprising a dipper having a movable closure, retaining means normally holding the closure in closed position, means constituting a source 90 of energy built up by the movement of the closure for rendering the closure retaining means inoperative, and means normally preventing release of said energy.

2. In combination with a dipper of the class 95 described having a movable closure, retaining means for keeping said closure shut, and spring means set by the closure for releasing the retaining means to allow the closure to open. 100

3. In combination with a dipper of the class described having a movable closure and a latch for keeping said closure shut, spring means set by the closure for retracting the latch to allow the closure to open, means for 105 transmitting movement of the spring means to the latch, and releasable means normally restraining the spring means from acting.

4. Apparatus of the class described comprising a dipper having a hinged door, a 110 sliding latch normally retaining said door in closed position, a spring set by the door constituting a source of stored-up energy for moving the latch to inoperative position, and releasable means normally preventing the 115 spring from acting.

5. In combination with a dipper of the class described having a door and locking means for the door comprising a latch and a keeper therefor, means set by the door for 120 withdrawing the latch from the keeper to permit the door to open, said means comprising a spring actuated element, connections between said element and the latch, and releasable means normally preventing said spring 125 actuated element from withdrawing the latch.

6. In combination with a dipper of the class described having a movable closure and retaining means for keeping said closure 130 shut, spring means for retracting the retain-

ing means to allow the closure to open, means for transmitting movement from the spring means to the retaining means, said transmitting means comprising a lever having a relatively short arm connected to the spring means, and a releasable catch device normally engaging a relatively long arm of the lever.

7. Apparatus of the class described comprising a dipper having a movable closure, retaining means normally positioned to hold said closure closed, a source of stored-up energy for moving the retaining means from normal position to permit the closure to open, means for releasing said energy, and means actuated by the load in the dipper for restoring said energy.

8. Apparatus of the class described comprising a dipper having a movable closure, a latch normally positioned to keep the closure closed, a source of stored-up energy for retracting the latch, means for releasing said energy, and means actuated by opening of the closure for restoring said energy.

9. Apparatus of the class described comprising a dipper having a swinging closure, a movable latch normally retaining the closure in closed position, a source of stored-up energy for retracting the latch, means for releasing said energy, and means actuated by the closure as it swings open for restoring said energy.

10. In combination with a dipper of the class described having a movable closure and a latch for keeping said closure shut, a spring constituting a source of stored-up energy for retracting the latch to allow the closure to open, means for transmitting movement from the spring to the latch, a releasable catch normally restraining the spring, and means for transmitting movement from the closure, as it opens, to the spring for restoring the latter to normal position after it has been released by operation of the catch.

11. In combination with a receptacle having a movable bolt carried by the closure and a keeper on the receptacle with which the bolt positively engages to lock the closure shut, a source of stored-up energy for withdrawing the bolt from the keeper to permit the closure to open, and means actuated by the closure, in opening, for restoring said energy.

12. In combination with a dipper of the class described having a door, and locking means for the door comprising a latch and a keeper therefor, a lever for withdrawing the latch from the keeper, connections between the lever and latch, a normally stressed spring tending to move the lever to withdraw the latch from the keeper, a releasable catch for the lever, and connections between the door and lever so constructed and arranged that when the door opens it moves the lever in a direction such as to stress the spring.

13. In combination with a dipper of the

class described having a movable closure, and a latch for keeping said closure shut, a spring for retracting the latch to allow the closure to open, means for transmitting movement from the spring to the latch, said transmitting means comprising a lever, a releasable retainer normally engaging the lever and thereby preventing the spring from acting, and means for transmitting movement from the closure to said lever.

14. In combination with a dipper of the class described having a door, and a latch normally holding the door closed, means for withdrawing the latch to permit the door to open, said means comprising a lever, a spring normally tending to move the lever to withdraw the latch, a releasable catch normally preventing movement of the lever by the spring, means for releasing the catch to permit the spring to withdraw the latch and allow the door to open, and connections between the door and lever such that when the door opens the lever is restored to normal position engaging the catch.

15. In combination with a dipper of the class described having a door and locking means for the door comprising a latch and a keeper therefor, means comprising a lever for withdrawing the latch from the keeper, a normally compressed spring tending to move the lever and withdraw the latch from the keeper, a catch normally engaging the lever to prevent its movement, means for moving the catch to release the lever thereby permitting the spring to expand and withdraw the latch to allow the door to open, and means actuated by the door as it opens for restoring the lever to normal position and for recompressing the spring.

16. In combination with a dipper of the class described having a door and locking means for the door comprising a latch and a keeper therefor, a lever for withdrawing the latch from the keeper, connections between the lever and latch, a normally stressed spring constituting a source of stored-up energy for actuating the lever to withdraw the latch from the keeper, a catch normally preventing movement of the lever, means for releasing the catch to permit the spring to move the lever and withdraw the latch to allow the door to open, and connections for transmitting movement from the door to the lever for restressing the spring.

17. In combination with a dipper of the class described having a door and locking means for the door comprising a latch and a keeper therefor, a lever for withdrawing the latch from the keeper, connections between the lever and latch, a normally stressed spring constituting a source of stored-up energy for actuating the lever to withdraw the latch from the keeper, a catch normally preventing movement of the lever, means for releasing the catch to permit the spring to

move the lever and withdraw the latch to allow the door to open, and means transmitting movement from the door to the lever for re-engaging the lever with its catch and for restressing the spring.

18. In combination with a dipper of the class described having a door and locking means for the door comprising a latch and a keeper therefor, a lever for withdrawing the latch from the keeper, connections between the lever and latch, a normally stressed spring constituting a source of stored-up energy for actuating the lever to withdraw the latch from the keeper, a catch normally preventing movement of the lever, means for releasing the catch to permit the spring to move the lever and withdraw the latch to allow the door to open, and connections comprising relatively movable abutment elements for transmitting movement from the door to the lever for re-engaging the lever with its catch and for restressing the spring.

19. In combination with a receptacle having a closure and locking means for the closure comprising a latch and a keeper therefor, a lever device comprising a short arm and a long arm, a spring connected to the short arm, a releasable catch normally engaging the long arm and thereby keeping the spring under stress, means for transmitting movement of the lever device to the latch for withdrawing the latter from its keeper to permit the closure to open, and lost motion connections between the closure and the long arm of the lever device.

20. In combination with a dipper of the class described having a handle, a hinged door, and locking means for the door comprising a latch and a keeper therefor, a rock-shaft mounted on the handle, a long lever arm and a short lever arm fixed to the shaft, a chain wrapped about the shaft and connected to the latch, a spring connected to the short lever arm, said spring normally being stressed and tending to swing the arm and rock the shaft thereby to withdraw the latch from the keeper, a catch normally engaging the long lever arm to prevent the spring from rocking the shaft, means for releasing the catch

from the arm, and telescoping links pivotally connected to the long lever arm and to the door, respectively, said links permitting movement of the long lever arm when released by the catch but transmitting movement from the opening door to the long lever arm for returning the latter to its normal position.

21. In combination with a dipper of the class described having a handle and a hinged door and locking means for the door comprising a latch and a keeper therefor, a rock-shaft mounted on the handle, a long lever arm and a short lever arm fixed to the shaft, a chain transmitting movement from the shaft to the latch, a spring connected to the short lever arm, said spring normally being stressed and tending to swing the arm and rock the shaft thereby to withdraw the latch from the keeper, a bell-crank lever having a roller on one arm normally engaging the long lever arm to prevent the spring from rocking the shaft, means for turning the bellcrank lever to disengage the roller from the long lever arm, and a pair of links having abutment elements, one link being pivotally connected to the door and the other to the long lever arm, the abutment elements of said links normally being separated to permit the long lever arm to move when disengaged by the roller but engaging as the door opens and thereby returning the long lever arm to normal position.

22. In combination with a dipper of the class described having a movable closure, and a latch for keeping said closure shut, a spring for retracting the latch to allow the closure to open, means for transmitting movement from the spring to the latch, said transmitting means comprising a rocking member, a releasable retainer normally engaging the rocking member and thereby preventing the spring from acting, and means for transmitting movement from the closure to said rocking member.

Signed by me at Boston, Massachusetts, 95 this 25th day of June, 1927.

WILLIAM M. HOUGHTON.
